Attorney

UNITED STATES PATENT OFFICE.

FRED L. GRIFFIN, OF BOZEMAN, MONTANA.

COMBINATION STEPLADDER AND STOOL.

Application filed February 4, 1922. Serial No. 534,011.

To all whom it may concern:

Be it known that I, FRED L. GRIFFIN, a citizen of the United States, residing at Bozeman, in the county of Gallatin and

5 State of Montana, have invented certain new and useful Improvements in Combination Stepladders and Stools, of which the following is a specification, reference being had therein to the accompanying drawing.

10 This invention relates to house-hold articles and has special reference to a combination stool and stepladder.

15 The principal object is to provide a simple, practical and staunch device of this character.

Other objects and advantages will appear in the further description of the invention.

20 Referring to the accompanying drawing forming part of this application, in which like reference characters indicate like parts:

Figure 1 is an isometric perspective view of the device when used as a stepladder; and

Figure 2 is a similar view of the same when used as a stool.

25 The device comprises a rigidly constructed four legged stool, the top 1 preferably being rectangular in shape and the legs 2 parallel with each other.

30 The pairs of legs on two opposite sides are provided with a plurality of vertically spaced horizontal rungs 3, they being rigidly fixed to the legs either by mortise and tenon, or in any other substantial manner. Intermediate of the lowermost rungs 3 and

35 rigidly fixed thereto in any desired manner is a comparatively wide step or shelf 4, it being positioned intermediate of what might be termed the front legs of the stool as well as between the rungs 3; that is to say it is

40 preferably positioned well forwardly in structure and forms the uppermost step of

the ladder when the stool is inverted, while at the same time forming a convenient platform for a sitter's feet who may be using the stool in such manner.

45 Intermediate of the next adjacent rungs 3 is a similar step 5, though positioned centrally in respect to the front and back legs of the stool, while intermediate of the uppermost rungs 3 and the back legs of the stool, 50 relatively in substantially the same relation to the legs and rungs as the step 4; is the third step 6 which forms the lowermost elevated step of the ladder when the stool is inverted for such use.

55 From the foregoing it is evident that I have devised an exceedingly simple, practical and staunch house-hold article, and one that is exceedingly dependable when being used as a stepladder, where so many somewhat similar devices are apt to fail.

60 Having thus described my invention, what I claim and desire to secure by Letters Patent, is:

65 A combined stool and stepladder consisting of four vertical legs rigidly braced on two sides of the rectangle formed thereby by transverse rungs; a top or seat rigidly supported on the legs at one end and covering the entire rectangle, and a series of 70 steps offset from each other to form an inclined flight extending from the seat to the free end of the legs, so that the structure forms a stool in one position and a stepladder when inverted.

75 In testimony whereof I hereunto affix my signature in the presence of two witnesses.

FRED L. GRIFFIN.
